UNITED STATES PATENT OFFICE.

HERBERT E. VAN DORN, OF CHICAGO, ILLINOIS, ASSIGNOR TO VAN DORN COUPLER COMPANY, OF CHICAGO, ILLINOIS, A CORPORATION OF ILLINOIS.

DRAFT-GEAR.

1,218,722.

Specification of Letters Patent. Patented Mar. 13, 1917.

Application filed June 18, 1915. Serial No. 34,788.

To all whom it may concern:

Be it known that I, HERBERT E. VAN DORN, a citizen of the United States, and a resident of the city of Chicago, in the county of Cook and State of Illinois, have invented certain new and useful Improvements in Draft-Gears; and I do hereby declare that the following is a full, clear, and exact description of the same, reference being had to the accompanying drawings, and to the numerals of reference marked thereon, which form a part of this specification.

Many types of draft gears have been designed wherein the impact is absorbed solely by springs or solely by friction, and other types have been constructed to absorb the shock both by means of springs and friction.

This invention relates to a draft gear of the latter type, that is, one in which the shock is absorbed by friction, as well as by springs, the friction elements of the device serving also to prevent the dangerous recoil of the springs. In my invention I provide a means for absorbing a sudden pull or buffing stress upon the drawbar of a car, and the amount of travel of the friction surfaces may be the same for both draft and buffing stresses, though preferably the travel for the latter ordinarily is greater. In this respect the permissible forward travel of the surfaces, due to a draft upon the gear, would be such as to prevent the cars pulling apart, but the rear travel may be considerable so as never to be fully utilized except under abnormal conditions, as in the event of collision, causing interlocking of the means on the bumpers, preventing telescoping of the cars. Draft gears with long travel will not be installed regularly on cars, except those equipped with anti-telescoping means. Practically all types of draft gears are rigidly secured to the underframing of a car structure but in the present invention I propose to embody a draft gear built into the drawbar of the car, so that the impact transmitted to the gear by cars which are situated upon a curve, is normal to the gear, thus obviating dangerous side thrusts which, in some instances, have proved disastrous to draft riggings.

However, my invention may be either mounted in the drawbar or rigidly connected to the underframing of the car with a slight modification, in each case the prin-

ciple of operation and association of the parts being practically identical.

It is an object of this invention to construct a draft gear in which friction elements are longitudinally disposed, so that by movement of one upon another due to an impact load, they are forced apart against the pressure of heavy springs, and the friction of said elements of course prevents the dangerous recoil of said springs after the shock is passed.

It is also an object of this invention to construct a draft gear consisting of pairs of friction elements opposed to one another and held apart by powerful springs, so that either a pull or impact transmitted to the gear will cause movement of certain of said friction elements to compress the springs, thus absorbing the load by spring pressure and friction, and obviating a shock to the support upon which the gear is mounted.

It is also an object of this invention to construct a draft gear provided with interfitting friction members angled with respect to one another such that the relative movement therebetween in different directions causes a different amount of separation of the elements and a plurality of powerful springs disposed to resist the movement of separation of said friction elements to absorb an impact transmitted thereto and tending to move the same longitudinally of one another.

It is also an object of this invention to construct a draft gear embracing a number of powerful compression springs disposed transversely in the gear and acting to oppose movement toward one another of movable friction elements which are permitted only a diagonal movement within the gear.

It is also an object of this invention to construct a draft gear comprising a casing with stationary elements removably mounted therein, and with complementary friction elements interfitting therewith and capable of diagonal movement with respect thereto, springs mounted between said removable friction elements to oppose their movement, and a yoke surrounding said movable elements and springs with wear-plates interposed between the ends of said elements and the followers.

It is also an object of this invention to

construct a draft and buffing gear wherein movable friction elements have diagonal movement with respect to a fixed friction element and have a transverse frictionally resisted movement with respect to another frictional element which is in turn longitudinally movable with respect to said fixed element.

It is furthermore an object of this invention to construct a draft gear in which the impact or pull is transmitted to a pair of friction elements capable of diagonal movement, and with compression springs disposed between said elements to oppose their movement toward one another, and with stationary complementary friction elements co-acting with said movable friction elements to oppose the diagonal movement thereof, thus absorbing a sudden shock and preventing recoil of the springs.

It is finally an object of this invention to construct a high capacity draft gear requiring only a small space for mounting and operation and consisting of few parts with means provided for simplifying the assembly and disassembly thereof.

The invention (in a preferred form) is illustrated in the drawings and hereinafter more fully described.

In the drawings:

Fig. 1 is a side elevation of a drawbar supporting a coupler with the coupler connected on a draft gear mounted in the drawbar and with a portion of the underframing of a car shown partly in section and partly in elevation.

Fig. 2 is a top plan view of the drawbar, draft gear and coupler construction illustrated in Fig. 1.

Fig. 3 is a transverse section taken on line 3—3 of Fig. 2, with parts in elevation.

Fig. 4 is a fragmentary section taken on line 4—4 of Fig. 3.

Fig. 5 is a section taken on line 5—5 of Fig. 1, with parts omitted.

Fig. 6 is a fragmentary section taken on line 6—6 of Fig. 1.

Fig. 7 is a similar view showing the position of the parts under buffing load.

Fig. 8 is a similar sectional view showing the position of the parts under pulling load.

Fig. 9 is a similar section showing the relation of the parts during the assembly operation thereof.

Fig. 10 is a side elevation of a modification showing a fragment of the underframing of the car structure with the draft gear rigidly mounted thereon and with the drawbar carrying the coupler pivoted upon the draft gear.

Fig. 11 is a fragmentary section with parts in elevation on line 11—11 of Fig. 10.

Fig. 12 is a fragmentary section on line 12—12 of Fig. 11.

Fig. 13 is an end elevation of the drawbar

and support therefor taken on line 13—13 of Fig. 10, with parts omitted.

As shown in the drawings:

As illustrated clearly in Fig. 1, a drawbar 1, is pivotally connected to the underframing 2, of a car by means of a pivot bolt 3, and at its forward end said drawbar is enlarged to afford a draft gear casing 4, from which the yoked end 5, of the strap of the draft gear projects. A coupler 6, is pivotally supported in said yoke 5, by means of a transverse pivot bolt 7, engaging through apertures in the yoke and the tail of the coupler. An arc shaped Z-bar guide or track 8, is secured at the forward end of the car structure beneath the platform, and formed on the upper side of said drawbar at the extremity of the draft gear casing 4, is a shoe 9, which engages over said guide or track 8, to support the outer end of the drawbar and yet permit the same to swing about its pivot.

A lip 10, is also formed on the end of the drawbar beneath said shoe 9, to engage beneath the guide member 8, and prevent the drawbar being lifted upwardly during coupling, which would probably result in the consequent destruction of the pivot bolt 3. Removably, but rigidly mounted within the draft gear casing 4, are a pair of similarly constructed friction plates 11, which have a series of abutments thereon, of which the inclined surfaces 12, on one side thereof are longer and at a less angle with the plates than the opposite shorter and steeper sides 13, of each of said abutments. Said friction plates 11, are mounted vertically within the draft gear casing lying against the inner surface of the respective side walls thereof, and with their rear ends abutting a shoulder 14, formed on the interior of the casing to prevent their moving. At their forward ends said friction plates are enlarged and apertured to receive bolts 15, which extend therethrough, and through the top and bottom walls of the casing 4, of the drawbar to hold said friction plates rigidly in position.

Slidable friction plates 16, of channel section are mounted within the casing as shown in Fig. 3. Said slidable friction plates 16, are provided on their outer surfaces with abutments having long and short angled sides complementary with the respective sides 12 and 13, of the abutments on the stationary friction plates 11, so that when the mechanism of the draft gear is in normal position said movable friction plates 16, lie closely against the plates 11, with the respective abutments on each thereof interfitting with one another. It is clearly evident, therefore, that a forward or rearward diagonal movement is the only possible movement permitted the movable friction plates 16, provided of course that dur-

ing such movement said plates 16, bear against and slide upon the fixed or stationary plates 11.

Formed upon the inner flat surfaces of said 5 slidable friction plates 16, are lugs 17 and 18, of which the lugs 17, are apertured for a purpose hereinafter pointed out. Small coiled spiral springs 19, are mounted between said 10 respective slidable plates 16, and each is held in position at its ends by a pair of said lugs in alinement with one another. Large heavy coil springs 20, are wound about said 15 springs 19, and also bear at their ends against the inner surfaces of said respective 20 slidable friction plates, so that said springs act to resist the movement of said plates toward one another. At the rear end of said slidable friction plates is mounted a rear follower plate 21, and similarly at the forward end of said friction plates is mounted a follower plate 22, and a strap 23, extends over and around and beneath said assembled plates and springs and is integral with the yoke head 5, projecting outwardly at the 25 front end of the draft gear casing. Each of said follower plates 21 and 22, respectively, is provided with a spring steel wear plate 24, and each of the ends of the respective slidable friction plates 16, is enlarged and recessed to receive wearing plates 25, to slide transversely on said wear plates 24.

As clearly shown in Fig. 3, the interior 30 of the draft gear casing has formed therein a short partition or guide members 26, extending longitudinally through the casing, at the top and bottom thereof, adapting said strap 23, to slide therebetween and also affording guides or stops to hold the stationary friction plates 11, in place by contact with the outer side surfaces thereof. Of course, with the device assembled and in normal condition the coiled springs are initially stressed a certain amount in order 45 to hold the parts rigidly associated under spring pressure with one another.

In order to facilitate assembly, temporary assembly bolts 27, are provided, as clearly shown in Fig. 9, which extend through apertures in the stationary friction plates 11, and through said apertures in the slidable plates 16, and upon being drawn up hold the plates 11, the plates 16, with the springs therebetween, and the strap engaged therearound, together with the followers, as a single unit, which may be slipped into the draft gear casing 4. After the elements have been inserted into the casing the assembly bolts 27, are loosened and withdrawn through apertures 28, which are positioned in the walls of the casing at proper points for this purpose.

Of course, after the unit is inserted within 55 the draft gear casing, the parts are rigidly held therein by the shoulders 14, against

which one end of the friction plates 11, abut and by the bolts 15, which extend through the draft gear casing and through the enlarged ends of the plates 11, already mentioned.

In the modification illustrated in Figs. 10 to 13 inclusive, practically the only difference of construction of the draft gear itself is in the casing, which instead of being an integral unit is composed of two parts, 70 bolted together with one part, the upper part, rigidly bolted to the underframing 2, of the car. Said upper part of the casing is denoted as a whole by the reference numeral 29, and the lower part of the casing 80 by the reference numeral 30, each of said casing sections being provided with registering apertured attaching lugs 31, through which extend attaching bolts 32. In this construction, a series of lugs 33, are provided in the side walls of said upper and lower casing sections respectively, as shown in dotted lines in Fig. 11, and stationary abutment friction plates 34, are recessed to fit over said lugs to prevent movement of 90 said friction plates which also bear at their rear ends against shoulders formed in the casing.

The movable friction plates and coiled springs, as well as the followers and wearing plates with the straps engaging therearound, are identical in form and construction with those described in the previous construction. However, in place of the yoke 5, of the prior construction, a yoke 35, integral with the strap 23, but provided with a vertical pivot bolt 36, serves to afford a pivotal support for the rear end of a drawbar 37. The outer end of said drawbar 37, is apertured transversely to receive a bolt 38, 105 therethrough for a coupler 6. Secured upon the upper surface of the outer end of the drawbar and extending longitudinally thereof is a T-shaped guide member 39, on which is slidably mounted a carriage 40. The upper side of said carriage 40, is provided with a transverse T-shaped groove adapted to engage over a curved guide member 41, to permit a swinging movement of the drawbar about its pivot 36, and support the same 115 properly aligned therewith at all times.

In this modified construction assembly bolts may or may not be used for the purpose of putting the device together, dependent upon whether or not the springs are 120 initially stressed. If no assembly bolts are used the bearing plates 34, are first placed into the lower section 30, and thereafter the plates 16, fitted therewithin with the un-stressed springs inserted therebetween. The 125 lower section and parts is then lifted upwardly as a whole to fit the friction members and springs into the upper casing 29, and said lower casing 30, is then bolted thereto. In practice, however, it will undoubtedly be 130

found desirable to initially stress the springs to secure greater frictional resistance to movement between the parts, thus requiring the use of assembly bolts.

5 The operation is as follows:

When the impact is delivered to the draft gear by the buffing of cars, either in coupling or switching, the yoke of the strap bears against the forward follower plate 22, 10 and acts to thrust the movable friction plates rearwardly. Owing to the interfitting abutments upon the stationary and movable friction plates, any rearward movement of the friction plates is accompanied 15 by a transverse movement thereof toward one another, resulting in a diagonal movement of each of the friction plates which is of course resisted by the friction between the stationary and movable plates, and due 20 to the transverse component of movement of the plates, the coiled springs are compressed. Another source of great frictional resistance to stresses imposed upon the gear is the friction either at the forward or rear end of 25 the gear, due to buffing or draft stresses, as the case may be, exerted between the spring wear plate 24, and plates 25, which have a transverse movement with respect to one another, but which move together longitudinally 30 within the stationary casing of the gear. The greater the stress imposed upon the gear, the greater the frictional resistance between the plates brought into action at one end of the gear.

35 As already pointed out, the sloping sides 12, of the stationary friction plate abutments, as well as the corresponding sides of the abutments on the movable friction plates, are the longer. This is to permit 40 more travel of the movable plates to take place for a certain compression of the springs under a buffing stress, while on the other hand the shorter and steeper sides 13, of the stationary friction plate abutments 45 and the corresponding sides on said movable plates permit a relatively short length of travel for the same compression of the springs under a pulling stress. This is desirable, inasmuch as the pulling stress transmitted 50 to the draft gear is generally never as great as a buffing stress, and consequently a longer travel and a greater interval of time is desirable to absorb a buffing stress. Then, too, the longer travel, as already 55 pointed out, is essential in instances where the cars are provided with anti-telescoping means which only come in play under abnormal conditions.

In the construction illustrated in Figs. 8 60 and 9, where the draft gear is embodied in the head of the drawbar, the rearward movement of the springs and friction plate is limited by lugs 42, provided on the interior of the casing to contact the rear follower 65 21. The forward travel of the parts

is limited by the enlarged portions on the forward ends of the stationary friction plates 11, through which the bolts 15, extend.

In the modification illustrated in Figs. 10 70 to 13 inclusive the travel of the parts is limited by the end walls of the casing itself, but it is only under the most extreme conditions in any case that the movable parts travel their entire permissible amplitude of 75 movement. It is obvious that owing to the great surface afforded between the friction elements, and due to the pressure of the springs a large frictional force must be overcome to move the parts within the draft 80 gear, and of course the frictional force acts counter to that of the springs after a shock has passed to absorb the recoil of the springs.

I am aware that various details of construction may be varied through a wide range without departing from the principles of this invention, and I therefore do not purpose limiting the patent granted otherwise than necessitated by the prior art.

I claim as my invention:

1. A draft gear embracing stationary friction elements, movable friction elements interfitting therewith, abutments on said respective stationary and movable friction elements to constrain said movable elements to move diagonally, resilient means interposed between said movable elements to resist movement thereof, and wear plates at each end of said movable friction elements adapted to absorb stresses and cause equal movement of said elements.

2. In a device of the class described a casing, stationary friction elements mounted therein, movable friction elements mounted adjacent thereto, resilient means interposed between said movable elements to resist movement thereof toward one another, and interfitting frictional engaging surfaces of different lengths on said respective stationary and movable friction elements to resist relative movement therebetween.

3. In a draft gear of the class described a casing, stationary friction elements disposed on each side thereof, movable friction elements mounted adjacent said stationary elements and interfitting therewith and capable of movement relative thereto, compression springs interposed between said movable elements adapted to resist movement thereof toward one another, follower plates mounted at each end of said movable elements and slidably within said casing, and a strap engaged around said follower elements to maintain said movable friction 120 elements and springs all associated with one another.

4. In a draft gear stationary friction elements, a plurality of inclined abutments thereon having long and short angled faces,

- movable friction elements, a plurality of inclined abutments thereon having long and short angled faces interfitting between said inclined abutments on said stationary elements, said abutments constraining said movable elements to move diagonally within said casing, and a plurality of resilient means interposed between said movable elements and bearing thereon to resist movement thereof, and increasing the friction between said movable and stationary friction elements as said resilient means are compressed.
5. In a device of the class described a casing, stationary friction means mounted therein, movable friction elements mounted in the casing adapted to slide on said stationary means, springs interposed between said movable elements adapted to move therewith, follower plates disposed at each end of said movable friction elements, wear plates interposed between said follower plates and the ends of said movable elements, and a strap engaging around said followers and said movable friction elements to maintain the same and said springs associated with one another.
6. In a device of the class described a casing, movable friction elements mounted therein capable only of diagonal movement therein, springs adapted to oppose the transverse component of said diagonal movement of said movable elements, wear plates contacting said movable elements to transmit a stress therethrough to move each of the same equally, and means within the casing to limit the travel of said movable elements.
7. In a device of the class described a casing, stationary friction means mounted therein, movable friction means mounted adjacent thereto, abutments on said respective stationary and movable friction means to cause said movable means to move diagonally of said stationary means, one side of said abutments on each of said means at a different angle than the other side, so that the diagonal movement of the movable means is different in opposite directions, and mechanisms acting to oppose the movement of said movable means and impel the same toward said stationary means.
8. In a device of the class described stationary friction plates, abutments thereon, one side of each thereof longer and at a different angle than the opposite side thereof, and movable friction plates interfitting with said stationary plates, and capable of a sliding movement on said abutments, said abutments due to their unequal sides adapted to permit a less travel of said movable means in one direction than in the other direction.
9. In a device of the class described stationary friction plates, abutments thereon, one side of each thereof longer and at a different angle than the opposite side thereof, movable friction plates interfitting with said stationary plates and capable of a sliding movement on said abutments, and resilient means between said movable plates; said abutments due to their unequal sides adapted to permit a less travel of said movable means in one direction than in the other direction with the same amount of compression on said resilient means.
10. A draft gear embracing stationary friction elements, movable friction elements interfitting therewith, abutments on said respective stationary and movable friction elements to constrain said movable elements to move diagonally, wear plates in the ends of said movable friction elements, wear plates bearing against the wear plates in the ends of said movable friction elements and extending across the space between said movable friction elements; followers reinforcing said second mentioned wear plates, and resilient means interposed between said movable friction elements to resist movement thereof.
11. In a device of the class described a casing, stationary friction means therein, movable friction elements mounted in the casing adapted to slide on said stationary means, wear plates in the end of said movable friction elements, wear plates bearing against the wear plates mounted in said movable friction elements and extending across the space therebetween, springs interposed between said movable elements, the wear plates bearing against wear plates in the ends of the movable friction elements and said movable friction elements with their wear plates, together with the springs, adapted to move as a unit, the springs resisting movement of the movable friction elements assisted in resisting such movement by the wear plates at their ends.
12. In a device of the class described a casing, stationary friction means therein, movable friction elements mounted in the casing adapted to slide on said stationary means, wear plates in the end of said movable friction elements, wear plates bearing against the wear plates mounted in said movable friction elements and extending across the space therebetween, springs interposed between said movable elements, the wear plates bearing against wear plates in the ends of the movable friction elements and said movable friction elements with their wear plates, together with the springs, adapted to move as a unit, the springs resisting movement of the movable friction elements assisted in resisting such movement by the wear plates at their ends, and follower plates disposed at each end of said movable friction elements with the respective first and second mentioned wear plates disposed therebetween.

13. In an absorption gear of the class described a plurality of friction mechanisms, acting by relative diagonal movement with respect to one another to resist stresses imposed upon the gear, and wear plates disposed at the ends thereof acting by relative transverse movement with respect to one another and the gear to absorb stresses imposed upon the gear.
14. In an absorption gear of the class described stationary friction means, friction means coacting therewith and movable diagonally with respect thereto to resist

stresses imposed on said gear, and friction wear plates coacting with one another movable longitudinally in said gear as a whole and having relative transverse movement to resist stresses imposed upon the gear. ¹⁵

In testimony whereof I have hereunto subscribed my name in the presence of two ²⁰ sub-scribing witnesses.
